K. P. A. SCHULTZ ET AL

WASHING MACHINE

Filed July 22, 1925

Patented Feb. 16, 1926.

UNITED STATES PATENT OFFICE.

KLARA PAULINE AUGUSTE SCHULTZ AND LOUIS WUEST, OF BROOKLYN, NEW YORK.

WASHING MACHINE.

Application filed July 22, 1925. Serial No. 45,196.

To all whom it may concern:

Be it known that I, KLARA PAULINE AUGUSTE SCHULTZ, a citizen of Germany, residing at Brooklyn, county of Kings, and State 5 of New York, and I, LOUIS WUEST, a citizen of the United States, residing at Brooklyn, county of Kings, and State of New York, have invented certain new and useful Improvements in Washing Machines, of which 10 the following is a specification.

This invention relates to improvements in washing machines, and has particular reference to a machine capable of being mounted within a wash tub.

15 An object of the invention is to provide an improved machine of simple and comparatively inexpensive construction which may be entirely confined within a wash tub and securely held therein against accidental displacement, and readily removed therefrom when so desired.

The above and other objects will appear more clearly from the following detailed description, when taken in connection with 25 the accompanying drawing, which illustrates a preferred embodiment of the inventive idea.

In the drawing—

Figure 1 is a top plan view of a wash tub 30 showing the improved washing machine therein;

Figure 2 is a section on the line 2—2 of Figure 1;

Figure 3 is a section on the line 3—3 of Figure 1;

Figure 4 is a detail elevation showing the manner of attaching a part of the machine in position; and

Figure 5 is a similar view illustrating 40 other attaching means.

Referring more particularly to the accompanying drawing the numeral 6 indicates a stationary wash tub of the usual type employed in homes and apartments and having 45 the hinged cover 7.

The machine of the present invention, which is designed to be mounted within the tub 6 and wholly confined therein below the upper margin of said tub, consists of a rotatable drum 8 having solid end walls and a 50 foraminous body 9 made of any suitable material. The body has a hinged cover 10 held in closed position by catches 11 and capable of being opened to permit of placing the 55 clothes to be washed in the drum and re-

moving the same therefrom after the washing operation.

One end wall of the drum is provided with a trunnion 12 which has a bearing in a supporting standard 13 the lower end of 60 which rests upon the bottom of the tub. The upper end of the standard is formed with a lateral extension 14 having a slot 15 therein. Associated with the extension 14 is a bracket 16 having flanges 17 which receive therebetween the upper edge of one of the side walls of the tub, said bracket being secured to the wall by a set screw 18 or other fastening device. The top of the bracket 16 overlaps the extension 14 and carries a bolt 19, 70 which projects through the slot 15 and has mounted thereon a wing nut 20 utilized to secure the standard in position within the tub. Thus it will be seen that suitable adjustments can be made between the standard 75 and bracket to accommodate the machine to tubs of various widths.

At the side of the tub opposite to that to which the bracket 16 is attached there is mounted a motor casing 21 supported by a 80 standard 21' and having brackets 22 similar to the bracket 16 capable of engaging over the upper edge of the adjacent tub wall and being rigidly secured thereto by set screws 23. The casing is thereby secured near the top of the tub.

The inner wall of the casing 21 is provided with a bearing for a trunnion 28 connected with the adjacent end of the drum 8, said trunnion being also provided with a 90 water-tight bushing 29 to prevent water from entering the casing.

The end of the trunnion 28 extends into the interior of the casing 21 and is provided with a gear 27 rigidly secured to said trunnion, which meshes with a worm 26 carried by one end of the shaft of an electric motor 24 which may be connected to a suitable source of power by a cord 25.

By means of such construction the power driving mechanism is all confined within the casing 21 and the casing furnishes a support for one end of the drum and by providing means for connecting said casing and the opposite end of the drum with supporting means and means for adjustably attaching said casing and drum to the walls of a stationary tub, a device is provided that is simple in construction, effective in operation, durable in use, occupying a minimum 100 105 110

of space, and adapted to be quickly mounted within tubs of varying lengths, and removed therefrom, and when not in use may be completely concealed by the lid or cover of the tubs.

What is claimed is:

A washing machine having a rotatable drum provided with trunnions, a watertight casing having a bearing supporting one of said trunnions, a gear fixedly secured to the end of said trunnion within said casing, an electric motor within said casing provided

with a shaft having a worm mounted thereon engaging the gear of said trunnion, a standard supporting said casing, a standard supporting the opposite trunnion of said drum, and means connected with said standards adapted to clamp the walls of a wash-tub.

In testimony whereof we have affixed our signatures.

KLARA PAULINE AUGUSTE SCHULTZ.
LOUIS WUEST.
